(57) **CLAIM**

I claim the ornamental design for an angled cuticle pusher, as shown and described.

DESCRIPTION

FIG. 1 is a perspective view showing a front side of one embodiment of my angled cuticle pusher showing a handle having an end portion with the end portion of the handle projecting from the handle, and a head portion of the end portion of the handle of the angled cuticle pusher proximate to a cuticle of a finger of a person.

FIG. 2 is a perspective view of the angled cuticle pusher of FIG. 1 showing the topside of the angled cuticle pusher.

FIG. 3 is a side elevational view of the angled cuticle pusher of FIG. 1 showing the backside of the angled cuticle pusher.

FIG. 4 is an end elevational view of the angled cuticle pusher of FIG. 1 showing the end portion of the handle of the angled cuticle pusher.

FIG. 5 is a perspective view of the angled cuticle pusher of FIG. 1 showing the bottom side of the angled cuticle pusher; and,

FIG. 6 is a topside view of the second embodiment of my angled cuticle pusher. It is understood that with the exception of the different angle of the pusher, all other views of the second embodiment are identical to the first embodiment.

The pattern is partially shown for convenience of illustration; it being understood that the pattern is uniformly continuous over the handle of the angled cuticle pusher.
